UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

WELT-BEATING MACHINE.

Application filed April 15, 1921. Serial No. 461,557.

To all whom it may concern:

Be it known that I, FRED N. LA CHAPELLE, a citizen of the United States, residing at Beverly, in the county of Essex and State 5 of Massachusetts, have invented certain new and useful Improvements in Welt-Beating Machines; and I do hereby declare the following to be a full, clear, and exact description of the invention, such as will enable 10 others skilled in the art to which it appertains to make and use the same.

The present invention relates to machines for use in the manufacture of shoes and more particularly to machines for use in beating 15 out a welt after it is attached to the upper and insole of a shoe to cause the welt to lie flat substantially in the plane of the insole.

The sidewise deflection of the welt in applying it to the toe of a shoe, particularly 20 of a pointed toe shoe, causes this portion of the welt to turn or curl up, and in order for the welt beating machines at present in common use to properly beat out the welt it is usually necessary to provide this portion 25 of the welt with a series of cuts or slashes in its under surface to enable the outer edge thereof to stretch sufficiently during the beating out operation to bring it into the plane of the insole. It has been found, 30 however, that in certain classes of work, such cutting or slashing of the welt is objectionable as the slashes tend to weaken the welt. Accordingly, the principal object of 35 the present invention is to provide a novel and improved welt beating machine which is adapted to properly beat out the welt without the necessity of subjecting the welt to a slashing operation.

The principal object of the invention is to 40 provide a novel and improved machine of this type which is adapted to operate effectively upon the portion of the welt extending about the toe of the shoe as well as upon the portions extending about the sides of the 45 shoe without the necessity of subjecting the welt to a slashing operation and without danger of weakening or otherwise injuring the welt.

With this object in view a feature of the 50 invention contemplates the provision in a welt beating machine of mechanism for beating out a welt which mechanism is capable of being controlled during the operation of the machine to vary the force of the 55 blows imparted to the outer edge portion of

the welt as compared with the force of the blows imparted to the inner edge portion. With this construction it will be apparent that during the operation of the machine when the toe of the shoe is reached, the welt 60 beating mechanism by being controlled to impart blows acting with greater force on the outer edge portion than on the inner edge portion of the welt to compensate for the curled up condition of the welt about 65 the toe of the shoe, will cause the outer edge portion of the welt to be stretched sufficiently to enable it to lie flat in the plane of the insole, and while operating on the remaining portions of the welt, the welt 70 beating mechanism may be controlled to operate in the usual manner to impart blows acting with substantially the same force on both the outer and inner edge portions of 75 the welt. It will also be apparent that with this construction it is not necessary for the welt to be slashed before or during the welt beating operation, and as the welt may be maintained substantially flat during the welt beating operation there is no danger of the 80 welt being scarred or otherwise injured. In the preferred embodiment of the invention the objects of the invention are attained by the provision of a reciprocating hammer and a cooperating anvil which are adapted 85 to be relatively adjusted during the operation of the machine to vary the angular relation of their working faces in such a manner that the force of the blow of the hammer on the outer edge portion of the welt may be 90 varied as desired. This result may, however, be accomplished in other ways, as by providing a wedge-shaped tool which may be inserted between the welt and the anvil to act as an auxiliary anvil to cooperate 95 with the hammer when the toe portion of the welt is reached, the tool being withdrawn while the machine is operating on the remaining portions of the welt to enable the anvil and hammer to act in the usual manner.

For the sake of simplicity of construction such relative adjustment of the hammer and anvil is preferably accomplished by adjusting the anvil, and in the preferred embodiment of the invention the anvil is adapted to be adjusted in an arc about a point substantially at the forward edge of the working face of the anvil so that the force of the blow on the outer edge portion of the 110

welt may be varied without materially affecting the force of the blow on the inner edge portion of the welt.

Other features of the invention consist in 5 certain constructions, arrangements and combinations of parts hereinafter described and claimed, the advantages of which will be obvious to those skilled in the art.

The several features of the invention will 10 be clearly understood from the following description and accompanying drawings, in which:

Figure 1 is a right side elevation of the upper portion of a welt beating machine 15 embodying the features in their preferred form with the casing of the machine shown in section; Figs. 2 and 3 are sectional plan views taken on the lines 2-2 and 3-3 of Fig. 1; Fig. 4 is a detail side elevation of 20 portions of the hammer and anvil engaging a welt with the anvil adjusted to cause the hammer to strike with greater force on the outer edge portion of the welt than on the inner edge portion; Fig. 5 is a side elevation 25 of a welt beating machine which is a modification of the machine illustrated in the preceding figures; Fig. 6 is a detail side elevation of a portion of the hammer, anvil and impact receiving tool or auxiliary anvil, 30 the hammer and auxiliary anvil being shown acting on the work; Fig. 7 is a plan view of the machine illustrated in Fig. 5; and Figs. 35 8 and 9 are detail plan and end elevations of an impact receiving tool or auxiliary anvil constituting a component part of the machine illustrated in Figs. 5 and 6.

The machine illustrated in Figs. 1 to 4, inclusive, of the drawings is provided with a vertically reciprocating hammer 2 and a co- 40 operating anvil 4. The hammer 2 is formed on the lower end of a downwardly spring pressed plunger rod 6 mounted in a cylindrical bearing 8 forming a part of a vertically reciprocating carrier 10. The carrier 45 10 is vertically guided by a rod 12 secured to the carrier and mounted to slide in a cylindrical bearing 14 formed on the forward portion of a bracket arm 16 projecting from a bearing post 18 of the frame of the 50 machine. The upper portion of the rod 12 extends through a vertical aperture in the rear end of an arm 20, forming a part of the carrier 10, and is clamped to the arm by a shoulder 22 formed on the rod 55 engaging the lower side of the arm and a clamping nut 23 screw-threaded on the upper end of the rod. The hammer and carrier are held from lateral movement by bosses 24 formed on opposite sides of the 60 arm 20 in sliding engagement with gibs 28 formed on the casing or frame of the machine. The carrier 10 is vertically reciprocated by a driving shaft 30 extending through and journaled in a bearing formed 65 at the upper end of the post 18. The con-

nection between the driving shaft 30 and the carrier 10 comprises a balance wheel 32 secured to the forward end of the shaft and carrying a roll 34 mounted eccentrically to the shaft which engages a horizontal groove 36 formed in the rear end of the arm 20 of the carrier. It will be apparent that this mechanism for actuating the hammer is of simple construction and will operate at high speed without undue shock or jar. 75

The rear portion of the anvil 4 is bifurcated to provide segmental arms 38 arranged at opposite sides of the cylindrical bearing 14 of the bracket arm 16. The outer sides of the segmental arms 38 are provided with grooves 40 which are concentric with a point at the forward edge of the working face of the anvil and are in sliding engagement with tongues or gibs 42 formed on opposite sides of the machine casing. With this construction it will be apparent that by shifting the anvil on the tongues or gibs 42 the working face of the anvil may be tilted about its forward edge as a center. The means for thus adjusting the anvil comprises a rock shaft 44 extending through and journaled in the bracket 16 between the cylindrical boss 14 and the bearing post 18. The connection between the shaft 44 and the anvil comprises an eccentric disk 46 secured to the right hand end of the shaft which engages a block 48 mounted to slide between gibs 50 projecting rearwardly from one of the segmental arms 38 of the anvil. An arm 52 is secured to the left hand end of the rock shaft 44 and is connected by a rod 54 with treadle mechanism at the base of the machine. 95

Upon depressing the treadle rod 54, the rear portion of the anvil is moved upwardly 105 on the gibs 42 to tilt the working face of the anvil upwardly at an angle to the working face of the hammer. Upon releasing the treadle rod 54 a spring 55 connected therewith acts to move the rear portion of the anvil downwardly to its normal position against a stop pin 56 secured to the lower end of one of the gibs 42 which positions the working face of the anvil in a horizontal plane or in a plane substantially parallel 110 with the working face of the hammer. While operating on the portions of the welt extending about the sides of the shoe, the anvil is thus held with its working face in a substantially horizontal plane, so that the hammer will operate with the same force on the outer and inner edge portion of the welt, and when the portion of the welt extending about the toe of the shoe is reached, the operator by depressing the treadle rod 54 115 will tilt the working face of the anvil to cause the hammer to act with greater force on the outer edge portion of the welt than on the inner edge portion, as illustrated in Fig. 4. It will be apparent that by depress- 120

ing the treadle rod 54 varying amounts that the operator may vary the relative beating out action or blows imparted by the hammer on the outer and inner edge portions of the 5 welt.

The machine illustrated in Figs. 5 to 9, inclusive, is provided with a stationary anvil 58 and a reciprocating hammer 60. The anvil 58 is formed on the forward end of a 10 bar 62 which is supported on a bracket 64 projecting from the frame of the machine and is secured to the bracket by a bolt 66. The bolt 66 extends through an elongated slot in the bracket and is screw threaded 15 into the bar 62 to provide for longitudinal adjustment of the anvil. The hammer 60 is formed on the lower end of a downwardly spring pressed plunger rod 68 mounted in a cylindrical bearing 70 formed on the forward 20 end of a rocking beam 72. The beam 72 is pivotally mounted midway of its ends on a stud shaft 74 supported by ears 76 on the machine frame. The rear end of the rocking beam 72 is bifurcated to engage a 25 block 78 pivotally mounted on an eccentric 80 formed on the driving shaft 82, by means of which the rocking beam is actuated to reciprocate the hammer. The hammer is so positioned that its working face is in a plane 30 substantially parallel with the working face of the anvil when the hammer strikes the work, and during the operation of the machine on the portions of the welt extending about the sides of the shoe the hammer and 35 anvil cooperate in the usual manner to beat out the welt. When the portion of the welt extending about the toe of the shoe is reached a tool or auxiliary anvil 84 is moved 40 into position between the welt and the anvil 58 to cooperate with the hammer in beating out this portion of the welt. The working face of the tool 84 is substantially of the same size and shape as the working face 45 of the anvil, and the tool is relatively thin and wedge-shaped to enable it to be easily inserted beneath the welt and to cause the outer edge portion of the welt to receive a greater stretching or beating out action than the inner edge portion by the impact of the 50 hammer as illustrated in Fig. 6.

The tool 84 is formed on the forward end of a plunger rod 86 extending through and mounted to slide in a cylindrical bearing 88 and held from turning movement by a 55 key 90 on the bearing engaging a longitudinal slot in the plunger. The plunger 86 is urged forwardly by a spring 92 coiled about the rod and interposed between a shoulder on the rod and a shoulder formed near the 60 rear end of the cylindrical bearing 88, and such forward movement of the rod is limited by stop nuts 94 screw-threaded on the rear end of the rod engaging the rear end of the bearing. The cylindrical bearing 88 65 is formed on a depending bracket 96 pro-

jecting from the forward end of a horizontal bar 98 which is mounted to slide in the machine frame. The sliding bar 98 is advanced and retracted to move the tool 84 into and out of operative position by means of a bell crank 100 pivotally mounted on a stud 102 secured to the frame of the machine. The upper end of an arm 103 of the bell crank 100 is bifurcated to engage a block 104 pivotally mounted on the sliding bar 98, and the other arm of the bell crank is connected by a rod 106 with treadle mechanism at the base of the machine. The arm 103 is urged rearwardly against a stop pin 108 secured to the machine frame to maintain the tool 84 in inoperative position by means of a coil spring 110 connected with the arm. With this construction it will be apparent that upon depressing the treadle rod 106 the tool 84 may be moved into operative position, and that upon releasing the treadle rod the spring 110 will return the tool to inoperative position. The yielding connection between the tool 84 and the sliding carrier 98 obviates any danger of the work or parts of the machine being injured in case it is attempted to advance the tool while the hammer is in engagement with the work.

The nature and scope of the present invention having been indicated and a machine embodying the several features of the invention in their preferred form having been specifically described, what is claimed is:—

1. A welt beating machine having, in combination, an anvil, a reciprocating hammer to cooperate with the anvil to beat out a welt, and means for relatively adjusting the hammer and anvil during the operation of the machine to vary the angular relation of the working faces of the hammer and anvil.

2. A welt beating machine having, in combination, an anvil, a reciprocating hammer for cooperating with the anvil to beat out a welt, and treadle controllable means for relatively adjusting the hammer and anvil to vary the angular relation of the working faces of the hammer and anvil.

3. A welt beating machine having, in combination, an anvil, a reciprocating hammer to cooperate with the anvil to beat out a welt, and means for adjusting the anvil during the operation of the machine to vary the angular relation of the working faces of the hammer and anvil.

4. A welt beating machine having, in combination, an anvil capable of being adjusted in an arc about a point located substantially at the forward edge of the working face thereof, and a reciprocating hammer to cooperate with the anvil to beat out a welt.

5. A welt beating machine having, in

combination, mechanism for beating out a welt capable of being controlled to vary the force of the blows on the outer edge portion of the welt as compared with the force of the 5 blows on the inner edge portion of the welt, and means for thus controlling said mechanism during the operation of the machine.

6. A welt beating machine having, in combination, a hammer, an anvil to cooperate therewith, means for adjusting the anvil in an arc about a point substantially at the forward edge of the working face of the anvil comprising a curved guiding member 10 on which the anvil is mounted to slide, a cam for moving the anvil on said curved guiding member, and treadle controllable means for actuating the cam.

7. A welt beating machine having, in combination, a hammer having a substantially flat working face, and mechanism to cooperate therewith to beat out a welt capable of being controlled during the operation of the machine to vary the force of the 20 blows on the outer edge portion as compared with the force of the blows on the inner edge portion of the welt.

8. A welt beating machine having, in combination, an anvil, a hammer cooperat- 25 ing therewith, a vertically reciprocating

carrier for the hammer, an arm projecting rearwardly from the carrier, a vertical rod extending through an aperture in the arm and secured to the arm, a bearing in which the rod is mounted to slide for guiding the 35 carrier vertically, means engaging opposite sides of the arm to prevent lateral movement of the carrier, a rotating shaft, and a roll carried by the shaft and mounted eccentrically to the shaft engaging a horizontal 40 slot in the rear end of said arm for actuating the carrier.

9. A welt beating machine having, in combination, an anvil, a hammer to cooperate therewith, a vertically reciprocating carrier for the hammer, a rotating balance wheel, and a roll eccentrically mounted on the balance wheel engaging a horizontal 45 slot in the carrier for actuating the carrier.

10. A welt beating machine having, in combination, mechanism for beating out a welt while maintaining the welt substantially flat capable of being controlled to vary the force of the blows on the outer edge portion of the welt as compared with the force 50 of the blows on the inner edge portion of the welt, and means for thus controlling said mechanism during the operation of the machine.

FRED N. LA CHAPELLE.
